UNITED STATES PATENT OFFICE

PHILIP GOVONI, OF WAREHAM, MASSACHUSETTS

DESIGN FOR A RAZOR BLADE HONE

Application filed August 24, 1931. Serial No. 40,910. Term of patent 14 years.

To all whom it may concern:

Be it known that I, PHILIP GOVONI, a citizen of the Kingdom of Italy, residing at Wareham, in the county of Plymouth and State of Massachusetts, have invented a new, original, and ornamental Design for Razor Blade Hone, of which the following is a specification, reference being had to the accompanying drawings, forming part thereof.

Figure 1 is a top plan view of the razor blade hone showing my new design.

Figure 2 is a view in front elevation thereof.

Figure 3 is a view in rear elevation thereof.

Figure 4 is an end view of the same.

I claim:

The ornamental design for razor blade hone as shown.

PHILIP GOVONI.
